D. C. RAUB.

Magazine Stove.

No. 18,469.

Patented Oct. 20, 1857.

UNITED STATES PATENT OFFICE.

D. CHRISTIAN RAUB, OF DAVENPORT, IOWA.

COAL-STOVE.

Specification of Letters Patent No. 18,469, dated October 20, 1857.

To all whom it may concern:

Be it known that I, D. CHRISTIAN RAUB, of Davenport, in the county of Scott and State of Iowa, have invented a new Principle 5 in the Construction of Coal-Burning Stoves; and I do hereby declare that the following is a full, clear, and exact description of the same, reference being made to the annexed drawings, forming a part of this specification, and the letters of reference marked thereon, in which—

Figure 1, represents an elevation of the stove. Fig. 2, represents a vertical central section through the same. Fig. 3 represents 15 a horizontal section taken at the line G. G. of Fig. 2, and Fig. 4 represents a plan of the movable grate shutters or dampers, underneath the fire chamber and its grates.

Similar letters of reference where they occur in the several figures denote like parts of 20 the stove in all of them.

This invention relates to a stove for burning coal or other material which packs down in the fire box, and requires a regulated 25 quantity of atmospheric air to promote proper combustion under all its conditions, and my invention consists more especially in the means by which I regulate the draft, thereby promoting uniform combustion, and 30 an economical dissemination of heat.

To enable others skilled in the art to make and use my invention, I will proceed to describe the same with reference to the drawings.

35 The base of the stove may be of rectangular form, and large enough to contain the ash box M, and to support the fire box or chamber D, and the cylinders composing the upper portion of the stove. There are two 40 cylinders, viz: An outer one A, and an inner one B, of such dimensions as will admit of a free passage for the smoke, gas, and other products of combustion to pass through, to the exit pipe z, o. These cylinders A, B, 45 have each a cover over their tops, viz: i, x, and the inner cylinder B, is to contain the charge of coal that supplies the fire chamber D, or the fire chamber only, may be filled through the cylinder B, by removing the two

50 covers i, x. There is a damper s in the exit pipe o; and a cap or cover l over the lower part of the pipe o, so that access may be had to it, for cleaning it out, repair, etc.

The under part, or bottom of the fire pot, box, or chamber D, is formed of segmental 55 grates D', D', D', D', so made as to leave an opening in the center of the said fire box. On the top part of the base of the stove is placed a conical, or a cylindrical shaped piece (marked C), with a conical cap on it. 60 This piece C, has air slots L, cut through it, to admit atmospheric air into the center of the burning mass. The conical cap is for spreading the charge of coal, and throwing it toward the sides of the fire box. The 65 lower end of the cone or cylinder C, is open, and communicates directly with the chamber inclosed by the base of the stove, air being admitted into said chamber, through the 70 openings or registers q.

Immediately underneath the segmental 75 grates D', are placed the sliding dampers F, F², F³, F⁴, so connected together by rods pivoted to the points X, Y, Z, as that by drawing out the rod o, the several slides F, F², F³, F⁴, move out on ways or guides and enlarge the space through which the air may pass up into the fire, and thus increase its 80 intensity. A reversed operation of the rod o, closes up this space, by moving all the slides toward a common center, and thus the draft through the grates D', is regulated with the greatest nicety. The cone C, stands 85 upon the plate Q; and the slides or grate coverers F, F², F³, F⁴, slide or rest upon the flanges v. W, W, W, W, &c., represent open 90 spaces, those at the four corners of the base being always uncovered, but those immediately in rear of the four slides, are open or closed, just as the slides may be for the time 95 being.

Having thus fully described the nature and object of my invention what I claim therein as new and desire to secure by Letters Patent is—

In combination with the fire box D, and its grates D', and perforated or slotted cone C, the slides F, F², F³, F⁴, arranged and operating in connection therewith, substantially in the manner, and for the purpose set 100 forth.

D. CHRISTIAN RAUB.
